CONTAINER FOR LIPSTICKS OR THE LIKE

Josef Rada, Union City, N. J.

Application July 20, 1955, Serial No. 523,202

5 Claims. (Cl. 206—56)

This invention relates to containers for lipsticks, other 15 types of cosmetics, or medicinal preparations, used in stick form.

The main object of the present invention is to provide a generally improved container of the type referred to, which will be so designed as to be capable of manufacture 20 at low cost, from inexpensive metal stampings or other cheap, easily obtainable and readily formed materials.

Another object is to provide a novel ejector means for the lipstick, so designed as to insure that the lipstick will be fully enclosed when not in use, so as to be kept 25 completely clean of dirt or other foreign particles, and so as, further, to insure that it will be kept fresh and will not deteriorate by exposure to air.

A further object of importance is to provide a container as described which will be compact in size and form, so as to occupy a minimum of space within a lady's purse.

A further object of importance is to provide, in the ejector means, a construction which will automatically provide an opening at the front end of the lipstick responsive to movement of the housed stick in a direction toward said front end, with said opening being provided coincident with the arrival of the stick at the front end of the associated casing, the construction further being such as to automatically cause the opening to be closed responsive to retraction of the stick into the casing.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view showing a lipstick container formed according to the present invention, in closed position.

Fig. 2 is a view similar to Fig. 1 in which the lipstick has been ejected.

Fig. 3 is an enlarged plan sectional view on line 3—3 of Fig. 1, the dotted lines showing the lipstick in extended position, parts being shown broken away.

Fig. 4 is a longitudinal sectional view on line 4—4 of Fig. 3.

Fig. 5 is a transverse sectional view, still further enlarged, on line 5—5 of Fig. 4.

Fig. 6 is a transverse sectional view on the same scale as Fig. 5, on line 6—6 of Fig. 4.

Fig. 7 is a perspective view of the casing, in blank.

Fig. 8 is a transverse sectional view through the blank, taken on line 8—8 of Fig. 7, the dotted lines showing the parts of the blank in their finally assembled relationship.

Fig. 9 is a perspective view of the lipstick support band per se.

Fig. 10 is a perspective view of the lipstick and its holder, per se.

Fig. 11 is a front elevational view of a modified form of support band, in blank.

2

Fig. 12 is an edge elevational view of the blank shown in Fig. 11, the dotted lines showing the modified band in its final form.

Fig. 13 is a perspective view of the modified band in its completed form, per se, portions being broken away.

The container constituting the present invention includes three main components, these being a housing or casing 10, a lipstick holder support band 12, and a lipstick 14 including a holder and stick element.

10 Considering first the construction of the housing, this in the illustrated example is formed from a single piece of thin sheet metal, which in blank appears as in Fig. 7, but it will be understood at this time that other materials, such as plastic, might be used.

The container is relatively elongated, and is of rectangular cross section, including a flat top wall 16 having rounded ends, a flat bottom wall 18 also having rounded ends and having its periphery in registration with that of the top wall, a first side wall 20, and an opposite side wall comprising coplanar, connected side wall portions 22, 24 integrally formed upon the top and bottom walls 16, 18, respectively, as shown to best advantage in Fig. 7.

20 The side walls are of such length as to terminate short of the rounded end portions of the top and bottom walls, and as a result, there is formed in the completed housing front and rear end openings 26, 28, with the construction being one that forms said end openings so that they extend along the sides of the housing a short distance as best shown in Figs. 1 and 2, the rounded end portions 30 providing top and bottom walls on the openings.

25 Formed in the side wall 20 is an elongated longitudinal slot 30, the opposite ends of which are closed and are disposed adjacent the respective openings 26, 28.

30 The top and bottom walls are formed with inwardly 35 facing, confronting, continuous peripheral grooves 32, 34, respectively, said grooves being formed by pressing the same out of the material of the blank as shown in Fig. 7.

35 Referring now to the lipstick support band, this has been generally designated at 12 and is shown per se in Fig. 9. The band is formed of an endless length of 40 spring steel, or alternatively, from thin plastic material having the characteristic of springable flexibility, thus to permit the top and bottom edges of the band to be engaged in the confronting grooves 32, 34. The band thus 45 assumes an oblong shape corresponding to that of the grooves, with rounded ends, and is slidable within the grooves when assembled with the housing.

45 Secured fixedly to one side wall of the band is an outwardly, laterally projecting handle 40, the base of which is extended through the slot 30 of the housing. Opposite the handle 40, the band is formed with an elongated, wide slot 38.

50 The lipstick 14 is provided with a cup 42 which in the 55 illustrated example is of rectangular conformation, one end of said cup being engaged in one end of the slot 38. The cup is fixedly secured to the band, and the lipstick 44 supported therein projects forwardly within the housing, in the space between the side walls of the band as 60 shown in Fig. 3.

65 In manufacturing the device, the band is engaged in one or the other of the openings 32, 34, after which the material of the blank is bent upwardly in the manner shown in Fig. 8, the side wall portions 22, 24 being brought together and being fixedly secured by spot welding, crimping, or in any other suitable manner. Prior to insertion of the band in the housing, the cup 42 is engaged therewith, and this completes the construction of the device.

70 In use, the container will normally be closed as shown in Fig. 1, with the handle 40 at the forward end of the slot 30 and the lipstick 40 retracted. In this position of

the parts, the slot 38 extends along the straight side wall of the band, opposite the handle as shown in Fig. 3.

When the lipstick is to be extended, the handle 40 is grasped and shifted to the dotted line position shown in Fig. 3, at the opposite end of the slot 30. This causes the band to travel within the grooves 18, 16, and when the handle 40 is moved to the left in Fig. 3, the slot 38 is shifted toward the front of the device, eventually extending across the opening 26, to provide, as shown in Fig. 2, an outlet for the lipstick. Meanwhile, the lipstick is moving forwardly, and the free end or tip of the same arrives at the front end of the casing approximately simultaneously with the uncovering of the opening 26. As a result, continued movement of the handle 40 to the left in Fig. 3 causes the lipstick to travel in an opposite direction, out of the slot 38 to the extended position shown in full lines in Fig. 2 and in dotted lines in Figs. 3 and 4.

When the lipstick is to be retracted, the handle is simply shifted in a return direction, and as the lipstick becomes fully withdrawn into the casing, the unslotted portion of the band will again move across the front of the housing to close the same.

It will be seen that the housing is completely closed when the lipstick is not in use, protecting the lipstick against dirt and other foreign particles, and also against deterioration caused by full exposure to atmosphere.

In Figs. 11-13, there is shown a modified lipstick support band 12^a, which is used with the cosmetic stick 44 and with the housing 10. The modified construction is illustrative of an arrangement wherein the lipstick support band can be formed entirely from a single length of sheet metal material, and will be so designed as to be integrally provided both with a handle and with a lipstick support cup or holder. The band 12^a, thus, includes an integral handle 40^a, and a stick support cup or holder 42^a.

Originally, the band in blank constitutes an elongated, rectangular length of thin sheet metal material, and cut in the blank, adjacent one end thereof, is a horizontally extending, U-shaped slit defining the portion of the blank that is to provide the handle 40^a. Approximately medially between the opposite ends of the blank, there is cut therein another horizontally extending, U-shaped slit, one end of which is rounded. The material of the blank is cut out at the rounded end of the slit, and between the legs of the U-shaped slit there is defined a flat tongue which is to form the stick support cup 42^a.

At the base of the tongue, there is defined a transverse bend line 46, and spaced apart along said bend line are V-shaped slits defining teeth 52. At the free end of the tongue similar teeth 54 are formed, and intermediate the opposite ends of the tongue, there are provided transverse, spaced bend lines 48, 50.

To form the band, the tongue is bent laterally along the line 46, and the teeth 52 projected laterally inwardly of the band as shown in Figs. 12 and 13. Then, the tongue is bent along line 48 in an opposite direction, and then bent once again, in the same direction as it was bent along the line 48, along the line 50. This provides a holder of U-shaped section as shown in Fig. 13, the teeth 54 being projected laterally, inwardly of the holder in confronting relation to the teeth 52. The bending of the tongue to the shape illustrated defines the slot 38^a in the completed band, and the handle 40^a is disposed opposite said slot and is struck laterally, outwardly from the material of the band as shown in Fig. 13. The end portions of the band are bent along curving lines so as to provide the oblong band with rounded ends as shown in dotted lines in Fig. 12, the opposite extremities of the blank abutting against one another as shown in Fig. 13. Said extremities of the blank need not be fixedly connected to one another, since the band will hold its shape when engaged in the grooves 32, 34, but if desired, they can be fixedly connected in a suitable manner.

The stick 44 is engaged in the U-shaped holder 42^a,

and the teeth 52, 54 will penetrate the same to insure its being properly held in position.

The construction of Figs. 11-13 is particularly adapted to facilitate production of the band from thin, spring steel material at a minimum of cost, so that said band and the casing 10 can both be formed from blanks of thin sheet metal material. The construction of Figs. 11-13 permits the entire device to be made from only two pieces of material, the blanks of which are shown in Figs. 7 and 11, respectively.

In use of the modified form, the operation of extending and retracting the lipstick is identical to that described in reference to the first form of the invention, movement of the handle 40^a in one direction causing movement of the lipstick in an opposite direction, for the purpose of extending or retracting the lipstick as the case may be.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. A container for a lipstick, comprising a housing formed open at, at least one end thereof, a continuous band slidably engaged in the housing and having a slot extending through a part of its circumference, said band in one position being disposed with its unslotted portion extending across said opening to close the housing at said one end thereof, and in another position having its slot registered with the opening to open the housing at said end, a handle on the band projecting out of the housing for shifting the band between said positions, and a lipstick holder carried by the band and shiftable away from said opening in the first position of said band to retract a lipstick supported thereby, said holder being shiftable in the direction of said opening in the second position of the band to extend the supported lipstick out of the housing through said opening, the band being formed from a single piece of thin, springable material, said holder and handle being integrally connected to the band.

2. A container for a lipstick, comprising a housing formed open at, at least one end thereof, a continuous band slidably engaged in the housing and having a slot extending through a part of its circumference, said band in one position being disposed with its unslotted portion extending across said opening to close the housing at said one end thereof, and in another position having its slot registered with the opening to open the housing at said end, a handle on the band projecting out of the housing for shifting the band between said positions, and a lipstick holder carried by the band and shiftable away from said opening in the first position of said band to retract a lipstick supported thereby, said holder being shiftable in the direction of said opening in the second position of the band to extend the supported lipstick out of the housing through said opening, the band being formed from a single piece of thin, springable material, said holder and handle being integrally connected to the band, said slot of the band defining between opposite walls thereof a tongue portion on said piece of material, and said tongue portion being bent to form the holder.

3. A container for a lipstick, comprising a housing formed open at, at least one end thereof, a continuous band slidably engaged in the housing and having a slot extending through a part of its circumference, said band in one position being disposed with its unslotted portion extending across said opening to close the housing at said one end thereof, and in another position having its slot registered with the opening to open the housing at said end, a handle on the band projecting out of the housing for shifting the band between said positions, and a lipstick holder carried by the band and shiftable away

from said opening in the first position of said band to retract a lipstick supported thereby, said holder being shiftable in the direction of said opening in the second position of the band to extend the supported lipstick out of the housing through said opening, the band being formed from a single piece of thin, springable material, said holder and handle being integrally connected to the band, said slot of the band defining between opposite walls thereof a tongue portion on said piece of material, and said tongue portion being bent to form the holder, the tongue being bent into a U-shape to receive the lipstick.

4. A container for a lipstick, comprising a housing formed open at, at least one end thereof, a continuous band slidably engaged in the housing and having a slot extending through a part of its circumference, said band in one position being disposed with its unslotted portion extending across said opening to close the housing at said one end thereof, and in another position having its slot registered with the opening to open the housing at said end, a handle on the band projecting out of the housing for shifting the band between said positions, and a lipstick holder carried by the band and shiftable away from said opening in the first position of said band to retract a lipstick supported thereby, said holder being shiftable in the direction of said opening in the second position of the band to extend the supported lipstick out of the housing through said opening, the band being formed from a single piece of thin, springable material, said holder and handle being integrally connected to the band, said slot of the band defining between opposite walls thereof a tongue portion on said piece of material, and said tongue portion being bent to form the holder, the tongue being bent into a U-shape to receive the lipstick, and being formed with inwardly project-

10

ing teeth on opposite side walls, adapted to engage in corresponding surfaces of the lipstick.

5. A container for a lipstick, comprising a housing formed open at, at least one end thereof, a continuous band slidably engaged in the housing and having a slot extending through a part of its circumference, said band in one position being disposed with its unslotted portion extending across said opening to close the housing at said one end thereof, and in another position having its slot registered with the opening to open the housing at said end, a handle on the band projecting out of the housing for shifting the band between said positions, and a lipstick holder carried by the band and shiftable away from said opening in the first position of said band to retract a lipstick supported thereby, said holder being shiftable in the direction of said opening in the second position of the band to extend the supported lipstick out of the housing through said opening, the band being formed from a single piece of thin, springable material, said holder and handle being integrally connected to the band, said slot of the band defining between opposite walls thereof a tongue portion on said piece of material, and said tongue portion being bent to form the holder, the tongue being struck out of the material of the band at a location spaced longitudinally of the band from the holder.

ing teeth on opposite side walls, adapted to engage in corresponding surfaces of the lipstick.

5. A container for a lipstick, comprising a housing formed open at, at least one end thereof, a continuous band slidably engaged in the housing and having a slot extending through a part of its circumference, said band in one position being disposed with its unslotted portion extending across said opening to close the housing at said one end thereof, and in another position having its slot registered with the opening to open the housing at said end, a handle on the band projecting out of the housing for shifting the band between said positions, and a lipstick holder carried by the band and shiftable away from said opening in the first position of said band to retract a lipstick supported thereby, said holder being shiftable in the direction of said opening in the second position of the band to extend the supported lipstick out of the housing through said opening, the band being formed from a single piece of thin, springable material, said holder and handle being integrally connected to the band, said slot of the band defining between opposite walls thereof a tongue portion on said piece of material, and said tongue portion being bent to form the holder, the tongue being struck out of the material of the band at a location spaced longitudinally of the band from the holder.
